SINGLE OR STAND-UP COLLAR IRONING AND CURLING MACHINE

Filed March 5, 1931

Fig. 1.

Fig. 2.

Fig. 3.

Inventor:—

John Chanl.

By his Attorney: *Walter Gunns*

UNITED STATES PATENT OFFICE

JOHN CHANT, OF FELIXSTOWE, ENGLAND

SINGLE OR STAND-UP COLLAR IRONING AND CURLING MACHINE

Application filed March 5, 1931, Serial No. 520,421, and in Great Britain February 26, 1930.

This invention refers to "single" or stand-up collar edge ironing and curling machines of the kind comprising a dampening roller, a grooved ironing roller, channel-shaped guides for leading the collar, top edge downwards, on to the dampening roller, and from the dampening roller to the ironing roller, one of said guides being inverted and pressing the collar downwards on to the dampening and ironing rollers, and an arrangement of yieldingly contacting rollers between which the collars pass prior to being discharged down a chute into a receiver.

The object of this invention is an improved construction of said type of machine.

The improved machine is illustrated in the accompanying drawings, wherein:—

Fig. 1 is a side elevation.

Fig. 2 a plan, and

Fig. 3 is a sectional plan (in part) of Fig. 1 on line $x-x$.

a is the cast-iron hollow base part of the machine with the major portion of its upper face inclined, the highest part being along the longitudinal edge a^1 and its lowest part being along the longitudinal edge a^2 . b is a fixed overhanging bracket, mounted on one end of the base part a . c is a driving pulley, mounted loosely on a shaft c^1 , and clutched thereto or declutched therefrom by a clutch controlled by a weighted lever d . e is a worm on a shaft c^1 , while f , g , h and i are four vertical spindles journaled in the bracket b . j and k are spur gear wheels keyed to the spindle f while l is a spur wheel keyed to the spindle g . m is a spur wheel keyed to the spindle h and n a spur wheel keyed to the spindle i . The several wheels k , l , m and n mesh as shown, and impart rotary motion to the spindle i , which at its lower end carries the bevel wheel o^1 , which latter meshes with a like wheel o^2 on the spindle of the ironing roller p . A further spur wheel q on a spindle q^1 meshes with both the wheel l and the wheel k . The spindle q^1 is journaled in the pivoted bracket r , which is pivoted at r^* and is acted upon by a spring s and link s^1 to yieldingly hold the wheels l , k , and q in mesh. Carried by the bracket r is a block r^1 with a curved and inclined face, see Fig. 3. Adj-

cent to such block and keyed to the spindle q^1 , is a conical roller t with its wider end lowermost and keyed to the spindles f and g are the rubber-tyred rollers u , u . The spindle q^1 , being carried by the pivoted bracket r , is movable towards and away from the rollers u , u , around which passes an endless belt v , the belt also passing around a conical jockey pulley v^1 carried by a lever v^2 , and acted upon by a spring v^3 and nut v^4 to tension the belt v . The belt v and the lever v^2 and spring v^3 may be dispensed with, and a separate rubber ring applied to each of the rollers u , u .

x is a water trough and x^1 , x^2 are dampening rollers. y is a fixed U-shaped guide member overlying the dampening rollers, and z is an inverted U-shaped weighted guide member, both supported in the fixed bracket z^1 and the weight member being provided with pins z^* , which project into the slots of the supporting bracket z^1 . On the top edge of the weighted guide member are vertical pins z^2 for carrying added weight members when required. In the lower edge of the guide member y is a gap y^1 , through which the dampening roller x^2 projects.

In proceeding to treat a stand-up collar, it is passed endwise and top edge downwards between the guide member y and weight member z , the lower edge of the collar contacting with the dampening roller x^2 , and being thereby dampened. The collar is pushed forward until its forward end passes over the ironing roller p when the dampened edge becomes ironed and given a smooth finish. The collar, after passing over the ironing roller is caught between the roller t and the rollers u , u , (see Fig. 3), which nipping it, cause it to become curled longitudinally. On leaving the rollers the collar meets the block r^1 over which it travels until clear of the rollers; when it falls down the inclined face of the machine base, top edge ironed and curled.

A sheet metal plate z^3 is provided to close in the space into which the curled collars pass after leaving the curling rollers. A removable cover b^1 is provided to enclose the

gear wheels and to protect same from dust, etc.

What I claim is:—

1. A stand-up collar edge-ironing and curling machine, comprising a base part with sloping floor, and an overhanging bracket at one end of said base part, a horizontal power shaft journaled in said bracket, and a vertical spindle also journaled in said bracket, a train of gear wheels intermediate of the power shaft and the vertical spindle, the first gear wheel receiving motion from the power shaft and the last wheel transmitting rotary motion to the vertical spindle, certain of the other gear wheels transmitting rotary motion to two further vertical spindles, a further and horizontal spindle adjacent to the lower end of the first-named vertical spindle, bevel gear wheels for transmitting motion from said vertical spindle to the horizontal spindle, a peripherally grooved ironing roller on the horizontal spindle, and two further rollers on the lower ends of said further vertical spindles lying below the said overhanging bracket, a lever pivoted on said overhanging bracket, and a conical curling roller journaled on a vertical pivot at one end of said lever, the narrower end of said further roller being uppermost, a rubber tyre for the other two of said rollers, and means for holding the three rollers normally in yielding contact, a stationary curved block adjacent the conical roller and carried by the same supporting lever, whereby the collars, after being curled, are directed on to the said sloping floor of the machine base, as set forth.
2. In a machine as claimed in claim 1, a water-holding trough secured to one end of the machine base, a dampening roller and means for axially supporting the roller above said trough, and a wheel within the trough for supplying water to the dampening roller, a pair of channel-shaped guides above the dampening roller and extending forwardly and rearwardly of said roller, the lower guide being gapped at a point above the dampening roller, a slotted bracket carried by the water trough by which the guides are supported, the lower guide being fixed to the bracket and pivot pins on the upper guide slidably engaging the slot of the bracket, said guides extending to a point near to the ironing roller and being in line with the groove of said roller, and the upper guide acting to press the collar to be ironed against the dampening roller and the ironing roller, as set forth.

In testimony whereof I have signed my name to this specification.

JOHN CHANT.
